UNITED STATES PATENT OFFICE.

MARTIN MEYER, OF OMAHA, NEBRASKA.

DESIGN FOR A CLINKER-TONGS.

49,906.

Specification for Design.

Patented Nov. 14, 1916.

Application filed July 25, 1916. Serial No. 111,253. Term of patent 14 years.

To all whom it may concern:

Be it known that I, MARTIN MEYER, a citizen of the United States, residing at Omaha, in the county of Douglas and State of Nebraska, have invented a new, original, and ornamental Design for a Clinker-Tongs, of which the following is a specification, reference being had to the accompanying drawing, forming a part thereof.

Figure 1 is a side view of the clinker tongs illustrating my new design. Fig. 2 is a plan view of the same.

I claim:

The original design for a clinker tongs, as shown.

In testimony whereof, I have affixed my signature in presence of two witnesses.

MARTIN MEYER.

Witnesses:

HIRAM A. STURGES,
ARTHUR H. STURGES.
